FLATIRON

Hyman D. Bowman, Pittsburgh, Pa.

Application August 29, 1935, Serial No. 38,421

7 Claims. (Cl. 38—74)

This invention relates to flatirons and more in particular to electrically heated flatirons.

One of the main objects of this invention is to provide a flatiron which is automatically raised above the ironing board a sufficient distance to eliminate all dangers of scorching or burning the goods that is being ironed, as soon as pressure on the handle of the iron is removed, such as may occur when the laundress leaves her work 10 and inadvertently fails to turn off the electric current.

Another object of this invention is to provide a self-raising flatiron which may be locked in its closed, operative position, if so desired, during 15 the working period or for the purpose of storing the flatiron away.

A further object of this invention is to provide a self-raising iron which is efficient in performing its particular function and which can be manufactured at relatively low cost.

Additional features and advantages of this invention will appear in the following description considered in connection with the accompanying drawing forming part of this application.

25 In the drawing:

Fig. 1 is a longitudinal sectional view showing one embodiment of my invention.

Fig. 2 is a perspective view of the sub-base used in Fig. 1.

30 Fig. 3 is a perspective view of a cam lever also used in Fig. 1.

Fig. 4 is an enlarged sectional view of one of the spring-supports employed in the embodiment shown in Fig. 1.

35 Referring to Fig. 1 in particular, the flatiron shown therein comprises a base-plate 1, upon which is located an electric heating element 2 and a cast iron core 3 suitably held together by a bolt 4, the latter serving also to secure the handle 5 and the cover 6 of the iron. Current is introduced into the heating element by means of the contact-pins 7 which are adapted to receive an electric-contact plug (not shown) of any desired commercial type.

40 This flatiron is mounted on a sub-base 8 being yieldingly supported by, preferably, three supporting-springs 9, resting on bosses 10, provided on the sub-base and bearing against the inside of the cover 6. Guide-sleeves 11, screwed on the 45 bosses 10, are used to prevent buckling of these springs and also to protect them somewhat from exposure to the intense heat produced by the heating element. As shown, suitable holes are provided in the base, heating element, and core 50 to freely accommodate these sleeves and the lat-

ter are provided at the top with flanges 12 which serve as stops limiting the upward lift of the flatiron proper, by contacting the bottom of the enlarged recesses 13 formed in the core. If desired, a post 14, extending through the flatiron proper, may be screwed into the sub-base to act as a locking device to releasably hold the base 1 in close contact with the sub-base 8. This post is provided with a notch 15 which may be engaged by the tapering cam 16 provided on the cam-lever 17 rotatably mounted on the bolt 4 and held in place by the bolt-nut 18.

The aggregate strength of the supporting springs 9 is slightly greater than the weight of the flatiron proper, so that only a light downward pressure on the handle is necessary to force the iron into intimate contact with the sub-base. On the other hand, as soon as said pressure is removed, the springs will force the iron up and provide sufficient clearance between it and the sub-base to eliminate all danger of scorching or burning the goods that is being ironed. Preferably, the flange 19 of the sub-base is suitably perforated, as at 20, to facilitate increased circulation of air between the sub-base and the iron, when the latter is in its raised, inactive position. It will be noted that when the flatiron is depressed on the sub-base, the downward sides of the cover 6 practically cover the perforations thereby reducing the loss of heat and thus concentrating same on the sub-base.

When the cam-lever is in the position shown in Fig. 1, that is, substantially cross-wise of the flatiron, the cam-flange of the lever does not engage the notch 15 in the post 14 and, therefore, the iron is free to rise under the upward pressure of the springs 9. However, when the iron is depressed on the sub-base and the cam-lever turned clockwise, the cam 16 will engage said notch and, owing to the bevelled shape of the former, the flatiron and the sub-base will be forced and locked together into intimate contact to facilitate the transfer of heat from the base 1 to the sub-base 8.

I claim:

1. In combination with a flatiron, a sub-base having a peripheral flange arranged to freely receive, surround, and guide the base of the flatiron and adapted to rest on the goods being ironed, and spring actuated means mounted on the sub-base to lift the flatiron above the sub-base when pressure thereon is removed.

2. In combination with a flatiron, a sub-base having a peripheral flange arranged to freely receive, surround, and guide the base of the flat-

iron and adapted to rest on the goods being ironed, and spring means mounted on the sub-base to lift the flatiron above the sub-base when pressure thereon is removed, the peripheral flange 5 of said sub-base having apertures to increase the circulation of air between said base and sub-base.

3. In combination with a flatiron, a sub-base therefor adapted to rest on the goods being 10 ironed; means positioned on the sub-base to automatically lift the flatiron above said sub-base when pressure on the flatiron is removed, and means to lock the flatiron in contact relation with the sub-base.

15 4. In combination with a flatiron, a sub-base therefor adapted to rest on the goods to be ironed; spring means positioned on the sub-base to automatically lift the flatiron above said sub-base when pressure on the flatiron is removed; a 20 cam-lever rotatably mounted on the flatiron; a post mounted on the sub-base and having a notch engageable by the cam-lever to lock the flatiron in contact relation with the sub-base.

5. In combination with a flatiron, a sub-base 25 therefor adapted to rest on the goods being ironed; spring means positioned on the sub-base

to automatically lift the flatiron above said sub-base when pressure on the flatiron is removed; a lever rotatably mounted on the flatiron; a tapered cam on the lever; a post mounted on the sub-base and having means engageable by said tapered cam to lock the flatiron in contact relation with the sub-base and vary the pressure thereon. 5

6. In combination with a flatiron, a sub-base therefor adapted to rest on the goods being 10 ironed; means positioned on the sub-base to automatically lift the flatiron above said sub-base when pressure on the flatiron is removed; and unitary means to lock the flatiron in contact relation with the sub-base and vary the pressure 15 thereon.

7. In combination with a flatiron, a sub-base therefor adapted to rest on the goods being ironed; means positioned on the sub-base to automatically lift the flatiron above said sub-base 20 when pressure on the flatiron is removed; and unitary self-locking means to lock the flatiron in contact relation with the sub-base and gradually vary the pressure thereon. 20
